UNITED STATES PATENT OFFICE

FRED A. NOETZLI, OF LOS ANGELES, CALIFORNIA, ASSIGNOR TO AMBURSEN CONSTRUCTION COMPANY, INCORPORATED, OF NEW YORK, N. Y., A CORPORATION OF NEW YORK

BUTTRESS TYPE DAM

Application filed May 14, 1930. Serial No. 452,270.

This invention relates to improvements in dams and particularly to dams of the buttress type employing buttress heads and buttress walls.

An object of the invention is to provide an improved dam construction employing buttress walls and buttress heads wherein the forward face of the buttress head is protected by a water proofing substance over which is cast a slab facing, provision being made for draining away water which may seep through the slab facing and collect against the water proofing substance. In this respect the present application may be considered as divisional of the subject matter disclosed in my copending application Serial No. 220,197, filed September 17, 1927. As a feature of the above outlined construction the improved dam is advantageous in that the interior of the buttress head is effectively protected by the water proofing substance and forces are transmitted through the slab facing and through the water proofing substance by direct compression so that a minimum, if any, bending moments will be developed in the concrete forming the buttress head.

Another object of the invention is to provide an improved dam of the buttress type wherein the buttress head is longitudinally divided by a joint enabling contraction along predetermined lines. This aspect of the invention contemplates the erection of a buttress type dam having large buttress heads wherein the distance between the sides of a buttress head exceeds fifty or sixty feet so that some provision must be made for allowing the concrete to contract on setting without resulting in the destruction of the dam. This aspect of the invention also contemplates the provision of drains located at the rearward ends of the joints to drain off water which may enter the joints, preventing the development of internal pressure on the interior of the buttress heads, and an important function of the drains also resides in the fact that they assist materially in the internal cooling of the dam.

A further object of the invention is to provide a dam of the headed buttress type wherein the buttress head is not only divided into

sections by a longitudinal joint but also by lateral joints, enabling the sections defined by the joints to move slightly with respect to each other, if such movement should be required due to settling of the foundation or earthquake faults. The arrangement of the lateral joints is such that forces transmitted through the laterally extended joints by the forward sections of the buttress head will be transmitted to the buttress wall by direct compression, developing a minimum, if any, bending moments in the buttress head.

Another object of the invention is to provide a dam having headed buttress walls wherein the heads are spaced apart with a bridging construction bridging the space between the heads and to provide such a connection between the bridging construction and the buttress heads that forces transmitted by the bridging constructions to the heads will be transmitted by direct compression so that a minimum, if any, bending moments will be developed in the heads.

Another object of the invention is to provide an improved method of constructing dams which have their forward or up stream faces provided with a layer of water proofing substance covered by a slab facing. The improved method facilitates the construction of such type of dam.

With the foregoing and other objects in view, which will be made manifest in the following detailed description, and specifically pointed out in the appended claims, reference is had to the accompanying drawings for an illustrative embodiment of the invention, wherein:

Fig. 1 is a vertical section through the improved dam and may be considered as having been taken upon the line 1—1 upon Fig. 2.

Fig. 2 is a horizontal section taken approximately upon the line 2—2 upon Fig. 1.

Fig. 3 is a horizontal section taken substantially upon the line 3—3 upon Fig. 1.

Fig. 4 is a horizontal section taken substantially upon the line 4—4 upon Fig. 1.

Referring to the accompanying drawings, wherein similar reference characters designate similar parts throughout, and considering first the construction of the dam near

100

its base, the improved dam comprises a plurality of parallel buttress walls 10, shown on Figure 1 as having their rear faces upwardly and forwardly inclined as at 11. The specific nature of the construction of the buttress walls may vary under different circumstances. Each of the buttress walls has at its forward or up stream end a buttress head, generally designated at 12, and in the construction illustrated the buttress heads 12 near the base of the dam are of such width that their sides are contiguous to one another. On the forward face of the buttress head there is positioned a water proofing substance indicated at 13 over which there is cast a slab facing 14. In the slab facing there are formed suitable drains indicated at 15 for draining off water which may seep through the slab facing 14 and collect against the water proofing substance 13, preventing the development of an internal pressure which might tend to separate the slab facing 14 from the water proofing substance 13 and the forward face of the buttress. The water proofing substance 13 may be of any suitable material but I prefer to use galvanized iron which may or may not be corrugated. Other substances carrying coatings of asphaltum may be employed for this purpose if so desired. In erecting the dam with the coating of water proofing substance and the slab facing I prefer to first position the water proofing substance in place and then pour the buttress heads and the slab facing simultaneously so that the buttress head and the slab facing will be erected together. This facilitates greatly the construction of the slab facing as on tall dams it is very frequently quite difficult to first pour the buttress head and subsequently apply the water proofing substance and pour the slab facing there against from the bottom upwardly. The improved method of simultaneously pouring the buttress head and the slab facing eliminates such difficulty.

The buttress heads 12 at the base of the dam are apt to be of considerable width, which may exceed fifty or sixty feet. In this construction some provision must be made to permit contraction of the concrete between the sides of the buttress head. In the upper portion of Figure 2 there is illustrated one construction for permitting such contraction. In this buttress head there is formed a longitudinal joint 16 dividing the buttress head into two sections 17 and 18. The joint is preferably stepped or keyed so that the sections 17 and 18 have their relative longitudinal displacement limited. This joint may be formed in any suitable manner, such as by positioning tarred paper in the longitudinal center of the buttress head which will effectively prevent the bonding of the concrete across the joint. Any other suitable method of establishing a joint at the

center of the buttress head may be employed. Suitable reinforcing bars, such as indicated at 19, may extend across the joint to effectively tie the sections 17 and 18 together without preventing the opening of the joint should variations in conditions so require. 70

At the rear end of the joint 16 there is formed a drain 20 which serves to carry off any water which may enter joint 16, preventing the development of pressure on the interior of the buttress head. This drain also facilitates the cooling of the interior of the buttress head. Suitable reinforcing bars, such as indicated at 21, may be positioned behind the drain to effectively prevent the extension of joint 16 beyond the drain into the buttress wall 10. 75

In the center portion of Figure 2 there is formed a second form of buttress head embodying the invention. In this construction 85 the buttress head is longitudinally divided by a joint 22, similar in construction to joint 16, and having at its rear end a drain 23. Lateral joints 24 and 25 extend laterally from the drain 23 and these joints may be 90 vertically stepped or keyed, as shown, to prevent lateral displacement between the sections and if desired they may also be horizontally stepped or keyed to prevent vertical displacements. The arrangement of 95 these joints is such that forces transmitted across them or from sections 26 and 27 to the buttress wall 10 will be transmitted by direct compression so that a minimum, if any, bending moments will be developed 100 on the interior of the buttress head. Suitable reinforcing bars 28 may be embedded in the forward end of the buttress wall 10 immediately behind the lateral joints 24 and 25. As shown upon the drawings, suitable water 105 stops 29 may extend across the joints 30 to prevent leakage.

The above described construction is employed near the base of the dam wherein the construction of the buttress walls and the 110 buttress heads must be comparatively massive. At higher locations on the dam, wherein the dam is not subjected to such high pressures, smaller buttress heads may be employed. On Figure 3 the smaller buttress heads are designated by the reference character 31. These buttress heads are shown in spaced relation to one another and if they are still of considerable width they may be provided with longitudinally extending joints 115 32 which may be similar in construction to the joints 16 or 22. A bridging construction indicated at 33 serves to bridge the space between adjacent buttress heads and in the construction shown in Figure 3 this bridging construction may be in the form of a flat slab. The line of juncture between the flat slab 33 and the buttress head 31 is such that it is approximately normal to a radius 34 from a center located near the rear of the buttress head 120 125 130

so that forces transmitted by the slab 33 to the buttress head will be transmitted by direct compression, thus developing a minimum, if any, bending moments on the interior of the buttress head.

Near the top of the dam still smaller buttress heads may be employed, such as are shown on Figure 4. These buttress heads are indicated at 35 and ordinarily will be of a sufficiently small width so that no longitudinal joints need be employed therein, however, should their width be fairly extensive, the longitudinal joints may be used if found desirable. By virtue of the fact that the buttress heads 35 are smaller, they are spaced from each other a greater distance and for these large distances and comparatively low pressures I find it desirable to employ an arch 36 as the bridging construction connecting adjacent buttress heads. In a similar manner the juncture between a buttress head and the end of the arch is arranged approximately normal to the radius from a center located near the rear of the buttress head so that forces transmitted by the arch to the buttress head will be transmitted by direct compression to eliminate bending moments being developed on the interior of the head.

It will be noted that the entire construction is such that the elimination of bending moments being developed in the buttress head is a primary objective. The shape of the faces of the buttress heads is shown as being angular in form so that forces developed on the faces of the buttress head will be transmitted to the interior and to the buttress wall by direct compression. While the buttress head is shown as having an angular face it will be readily understood that a round face may be employed if desired. Such a round face as disclosed in my prior Patent No. 1,681,427, issued August 21, 1928, may be employed if desired. Where the shape of the face of the buttress head is formed in this manner the forces transmitted through the slab facing 14 and through the water proofing substance will likewise be transmitted by direct compression eliminating bending moments.

Likewise where spaced buttress heads are employed with bridging constructions between them, bending moments are effectively eliminated. The improved construction also provides for contraction of the concrete on expansive buttress heads and effectively prevents the development of internal pressure due to any water entering the longitudinal joints. At the same time it provides a construction facilitating the internal cooling.

While all of the various constructions are herein shown as being incorporated in the same dam, it will be readily understood that all of the various constructions need not be associated together in the same structure. As conditions vary either of the constructions disclosed on Figure 2 may be used alone, with

or without the constructions disclosed in Figures 3 and 4, and likewise in certain types of dams the construction disclosed in Figure 3 may be used alone without being arranged in conjunction with the other constructions. The same applies to the construction disclosed in Figure 4.

Various changes may be made in the details of construction without departing from the spirit or scope of the invention as defined by the appended claims.

I claim:

1. In a dam, a buttress wall having a buttress head, the buttress head having a vertically extending joint formed therein extending from adjacent its forward face rearwardly, there being a drain formed in the buttress head providing for draining off water which may enter the joint.

2. In a dam, a buttress wall having a buttress head, there being a water proofing substance over the forward face of the buttress head, and a slab facing over the water proofing substance, there being drains located in the facing next to the water proofing substance for draining off any water tending to collect against the water proofing substance.

3. In a dam, a buttress wall having a buttress head, there being a water proofing substance over the forward face of the buttress head, and a slab facing over the water proofing substance, there being a vertically extending joint in the buttress head extending rearwardly from its forward face.

4. In a dam, a buttress wall having a buttress head, there being a vertically extending joint formed in the buttress head extending rearwardly from its forward face, and means for preventing material displacements between the sections of the buttress head defined by the joint.

5. In a dam, a buttress wall having a buttress head, there being a vertically extending joint formed in the buttress head extending rearwardly from its forward face, there being additional upwardly extending joints extending laterally from near the rearward end of the first mentioned joint.

6. In a dam, a buttress wall having a buttress head, there being a vertically extending joint formed in the buttress head extending rearwardly from its forward face, there being additional upwardly extending joints extending laterally from the rearward end of the first mentioned joint, and a drain located at the juncture.

7. In a dam, a buttress wall having a buttress head, there being a vertically extending joint formed in the buttress head extending rearwardly from its forward face, there being additional upwardly extending joints extending laterally from the rearward end of the first mentioned joint, said joints being stepped or keyed to prevent displacement.

8. The method of pouring a headed but-

tress type dam which comprises positioning a water proofing substance adjacent what is to be the forward face of the dam, pouring the buttress head behind the water proofing substance, and simultaneously pouring a slab facing against the forward side of the water proofing substance.

9. The method of pouring a buttress type dam having a joint extending upwardly and rearwardly adjacent its forward face, which comprises pouring first a portion of the dam, then placing in advance of pouring and holding in place during pouring a sheet of material extending in the direction of said joint, and then pouring concrete substantially simultaneously on both sides of said sheet.

10. The method of pouring a headed buttress dam as described in claim 9, by further placing adjacent to said sheet means for disposing of water that might accumulate in said joint.

11. A dam comprising a buttress wall and a buttress head supporting the water pressure, the upstream face of said buttress head having such a configuration that the water pressure is transmitted by the buttress head to the buttress wall substantially by direct compression, and a joint in said buttress head extending substantially parallel to the upstream face.

12. In a dam, a buttress wall, a buttress head for the wall portions of which project laterally beyond the sides of the wall, there being a vertically arranged expansion joint formed in the buttress head extending from its forward face rearwardly.

13. In a dam, a buttress wall, a buttress head for the wall portions of which project laterally beyond the sides of the wall, there being a vertically arranged expansion joint formed in the buttress head extending from its forward face rearwardly, and means providing a water drain at the rear end of said expansion joint.

14. In a dam, a buttress wall, a buttress head for the wall portions of which project laterally beyond the sides of the wall, there being a vertically arranged expansion joint formed in the buttress head extending from its forward face rearwardly, said joint being irregular so as to lock the portions of the buttress head defined thereby against material relative displacements.

15. In a dam, a plurality of buttress walls, each buttress wall having a buttress head portions of which project laterally beyond the sides of the wall, said buttress heads being contiguously positioned and being defined from each other by vertical joints, there being vertically extending expansion joints formed in the buttress heads which extend from their forward faces rearwardly.

16. In a dam, a plurality of buttress walls, each buttress wall having a buttress head portions of which project laterally beyond

the sides of the wall, said buttress heads being contiguously positioned and being defined from each other by vertical joints, there being vertically extending expansion joints formed in the buttress heads which extend from their forward faces rearwardly, and water stops extending across both sets of joints.

17. In a dam, a buttress wall, a buttress head for the wall portions of which project laterally beyond the sides of the wall and having portions of its water face near its center extending farther upstream than portions at its sides, there being a vertically arranged expansion joint formed in the buttress head extending from its forward face rearwardly, and additional expansion joints diverging rearwardly from the rear end of said expansion joint.

18. In a dam, a plurality of buttress walls, each buttress wall having a buttress head, said buttress heads being spaced from each other, means bridging the space between adjacent buttress heads, the engaging surface between said means and a buttress head being arranged approximately perpendicular to a radius drawn from a point located downstream of said surface.

19. In a dam, a plurality of buttress walls, each buttress wall having a buttress head portions of which project laterally beyond the sides of the wall, said buttress heads being spaced from each other, bridging means bridging the space between adjacent buttress heads, portions of the buttress heads between the bridging means being exposed to water pressure, there being vertically extending expansion joints formed in the buttress heads extending from their forward faces rearwardly.

20. In a dam, a plurality of buttress walls, each buttress wall having a buttress head portions of which project laterally beyond the sides of the wall, said buttress heads being spaced from each other, bridging slabs bridging the space between adjacent buttress heads, portions of the buttress heads between the bridging slabs being exposed to water pressure, the engaging surfaces between a bridging slab and a buttress head being forwardly convergent, in such a manner that the reaction force due to the pressure of the water upon the bridging slab will not produce any tension stresses in the portions of the buttress head extending laterally beyond the sides of the buttress wall.

21. In a dam, a buttress wall which is structurally substantially independent of the rest of the dam and having a buttress head subject to water pressure, there being an expansion joint vertically arranged in the buttress head and extending from adjacent its forward face rearwardly.

22. In a dam, a buttress wall which is structurally substantially independent of the rest of the dam and having a buttress head subject

to water pressure, there being an expansion joint vertically arranged in the buttress head and extending from adjacent its forward face rearwardly, and means arranged adjacent the rear end of said expansion joint for preventing extension of the joint.

23. In a dam, a plurality of substantially independent buttress walls, at least some of said walls having buttress heads subject to water pressure, there being an expansion joint vertically arranged in each buttress head and extending from adjacent its forward face rearwardly, a waterproofing substance over the forward end of the joint, and a slab facing over the waterproofing substance.

24. In a dam, a buttress wall having a buttress head subject to water pressure, there being an expansion joint vertically arranged in the buttress head and extending from adjacent its forward face rearwardly, means tending to prevent water from entering the forward end of the joint, and means for draining off water which might enter the joint.

25. In testimony whereof I have signed my name to this specification.

FRED A. NOETZLI.
